UNITED STATES PATENT OFFICE.

WALTER N. AUCLAIR, OF LENTS, OREGON.

MAIL-CATCHER.

1,185,043.

Specification of Letters Patent.

Patented May 30, 1916.

Application filed April 20, 1915. Serial No. 22,697.

To all whom it may concern:

Be it known that I, WALTER N. AUCLAIR, a citizen of the United States, residing at Lents, in the county of Multnomah and 5 State of Oregon, have invented certain new and useful Improvements in Mail-Catchers, of which the following is a specification.

This invention relates to an improved mail catcher and the principal object of 10 the invention is to provide a mail catcher so constructed that a mail bag may be taken from a car while in motion, the sack being suspended from a bar releasably held in an operative position beneath the carrying 15 crane and dropped into a receptacle mounted adjacent the track as the train passes the station.

Another object of the invention is to provide improved means for releasably holding 20 the carrying bars in an operative position.

Another object of the invention is to provide an improved type of receptacle for catching the sack after the trigger has been moved to the position to release the carrying 25 bar.

Another object of the invention is to so mount the receptacle that it may rotate when the sack is dropped into the same.

Another object of the invention is to so 30 construct this receptacle that it may be placed between the track for use in connection with trains going in opposite directions or may be used in connection with a single track line for taking mail sacks from trains 35 going in both directions.

Another object of the invention is to provide the receptacle with improved means for causing the receptacle to rotate when the means is struck by the mail sack.

40 Another object of the invention is to provide an improved type of crane arm for carrying the supporting bar and to provide improved means for guiding the movement of the crane into and out of the car.

45 This invention is illustrated in the accompanying drawings, wherein:—

Figure 1 is a view showing the mail transferring mechanism in elevation with the car shown in rear elevation and having one 50 wall broken away to show the manner of mounting the crane in the car. Fig. 2 is a view showing the receptacle or bowl in vertical section with its standard in elevation.

Fig. 3 is a top plan view of the receiving 55 device shown in Fig. 3. Fig. 4 is a per-

spective view of the crane together with its carrying standard and guiding track.

In describing this invention reference will first be had to the carrying mechanism mounted in the mail car 10 so that the sack 60 11 can be connected with the carrying bar 12 while the crane arm 13 is still within the car and the crane arm then swung outwardly through the doorway of the car to a position in which the handle 14 of the 65 trigger 15 can be engaged by the receiving mechanism to be hereinafter described. This crane arm 13 is pivotally mounted upon the bearing finger 16 of the standard 17 and is provided at its inner end portion 70 with an extension 18 terminating in the harp 19 in which the flanged roller 20 is rotatably mounted. This roller 20 is flanged so that the flanges may be positioned above and below the track 21 which 75 track is connected with the wall of the car by fasteners 21' as shown in Fig. 1 and supported from the roof of the car by means of the hanger 22. Therefore when the roller 20 is in place the crane arm will be guided 80 in its swinging movement and have its inner end portion supported so that the strain will be removed from the pivot pin 23 passing through the crane arm 13 and thus the pivot pin prevented from being bent or 85 broken and the crane arm prevented from binding upon the bearing finger 26 which binding would tend to prevent the crane arm from moving easily.

The carrying bar 12 when in an operative 90 position extends horizontally beneath the outer end portion of the crane arm 13 and has its inner end portion connected with the crane arm by means of the link 13' and its outer end portion positioned upon the 95 trigger 15 between the lips 24 of the latch 25. Therefore the carrying bar will be prevented from slipping off of the trigger plate 15 and will be releasably held in the elevated position until the trigger is moved to 100 the dotted line position shown in Fig. 4. When this trigger is moved to the dotted line position the carrying bar will be released and will drop to the position indicated by the dotted lines thus releasing the 105 mail bag and permitting it to drop into the receptacle.

The receiving mechanism which is shown in Figs. 1, 2 and 3 will now be described. The standard 26 of this receiving mecha- 110

nism is embedded in the ground adjacent the track and is provided with an enlarged base 27 providing a firmer foundation and also providing a support for the bearing 5 collar 28 upon which the bearing balls 29 are positioned. It is of course obvious that if desired the bearing 28 could be cast integral with the base 27 of the standard thus providing a more rigid structure. Upon 10 this standard 26 there is rotatably mounted a sleeve 30 which carries the bowl or receptacle 31 and has its lower end portion formed into a bearing collar 32 having a track formed therein to receive the bearing 15 balls 29. Therefore there will be no binding at the lower end portion of the receptacle and the receptacle will turn freely. The upper end portion of this sleeve is also provided with a bearing collar 33 which carries the bearing balls 34 positioned between the bearing collar 33 of the sleeve and the bearing collar 35 adjustably mounted upon the standard above the sleeve and releasably held in an adjusted position by means of the 20 set screw 36. By moving the bearing collar 35 upon the standard the amount of pressure placed upon the bearing balls can be regulated and through this means the freedom with which the bowl or receptacle is 25 rotated may be controlled. It is desired to have the bowl rotate when the mail bags drop into the same and in order to accomplish this there has been provided abutment plates 37 extending from the bearing collar 33 to the bottom of the bowl. As the train 30 passes the track device the handle 14 of the trigger will strike one of the releasing rods 38 carried by the rod 39 and the trigger will thus be moved to a position to release the 35 carrying bar 12 and permit the sack to drop into the bowl. In doing so the sack will strike one of the abutment plates 37 thus causing the receptacle to rotate upon the standard 26 and take up the force of the 40 blow received. This will prevent the contents of the mail sack from being injured and will also prevent danger of the mail bags being deflected and dropping upon the ground instead of into the receptacle. 45 From the above description the operation of the device will be readily understood, the mail clerk of course first placing the sack upon the carrying bar 12 and then swinging the crane arm outwardly to a position in 50

which the trigger may be moved to a released position by one of the rods 38. The crane arm is of course then swung back into the mail car after the sack has been delivered.

In order to permit a sack to be taken 60 from the station a suitable collecting hook 40 of any desired type may be mounted in the doorway of the mail car and provided with a handle 41 so that it may be moved into an operative position as shown in 65 Fig. 1.

What is claimed is:—

1. In a mail handling apparatus a track device comprising a standard, a sleeve rotatably mounted upon said standard, a receptacle carried by said sleeve, abutment plates carried by said sleeve and extending to the outer edge of said receptacle and above the receptacle, and trigger actuating means carried by said standard. 70

2. In a mail handling apparatus a track device comprising a standard, a sleeve rotatably mounted upon said standard, a receptacle carried by said sleeve, abutment plates carried by said sleeve and extending 80 to the outer edge of said receptacle and means carried by said standard for actuating the trigger of a train device.

3. In a mail handling apparatus a track device comprising a standard, a sleeve rotatably mounted upon said standard, a receptacle carried by said sleeve and being of less height than said sleeve, abutment plates carried by said sleeve and extending the full height thereof and from said sleeve to the 90 outer edge of said receptacle, and means carried by said standard for actuating a trigger forming part of a train device. 85

4. A mail catcher including a track device comprising a standard, a sleeve rotatably mounted upon said standard, a receptacle carried by said sleeve and of less height than the sleeve, abutment plates carried by said sleeve and extending from the upper end portion of said sleeve into said receptacle, and trigger actuating means extending 100 from said standard. 95

In testimony whereof I affix my signature in presence of two witnesses.

WALTER N. AUCLAIR.
